UNITED STATES PATENT OFFICE.

JOHN ALLEN HEANY, OF NEW HAVEN, CONNECTICUT, ASSIGNOR TO LINDSAY AUTO PARTS COMPANY, OF INDIANAPOLIS, INDIANA, A CORPORATION OF INDIANA.

IGNITION DEVICE FOR MOTOR-VEHICLES.

1,305,601.

Specification of Letters Patent.

Patented June 3, 1919.

Original application filed July 27, 1910, Serial No. 574,030. Divided and this application filed July 30, 1918.
Serial No. 247,371.

To all whom it may concern:

Be it known that I, JOHN ALLEN HEANY, a citizen of the United States, residing at New Haven, in the county of New Haven 5 and State of Connecticut, have invented certain new and useful Improvements in Ignition Devices for Motor-Vehicles, of which I declare the following to be a full, clear, and exact description.

10 This invention relates particularly to that type of dynamo electric machines, which have gas engine ignition mechanism incorporated in their structure. This application is a division of my co-pending application, Serial No. 203,171, filed November 21, 1917, which, in turn, is a division of my co-pending application, Serial No. 574,030, filed July 27, 1910.

15 The object of the invention is to embody in a single unit, a dynamo electric machine, a distributor, and a timer for internal combustion engines. Another object is to dispose the ignition elements in the dynamo, so that they will be easily accessible and detachable, and have a direct positive driving relationship with the dynamo armature shaft. Further objects, and objects relating to economies of manufacture and details of construction, will definitely appear from the 20 detailed description to follow.

25 I accomplish the objects of my invention by the devices described in the following specification; my invention is clearly defined and pointed out in the appended claims.

30 A structure constituting a preferred embodiment of my invention is illustrated in the accompanying drawings, forming a part of this specification, in which—

35 Figure I is a view showing the dynamo in place on an automobile chassis;

40 Fig. II is a diagrammatical view illustrating the electrical devices connected in proper circuit;

45 Fig. III is a view of the dynamo with the ignition devices shown in section;

50 Fig. IV is a sectional end view of the machine taken substantially on the line IV—IV of Fig. III;

55 Fig. V is a detail sectional view of the automatic switch controlling device.

Similar reference characters refer to similar parts throughout the several views, and

the sectional views are taken looking in the direction of the little arrows at the ends of the section lines.

55 In the accompanying drawings, the dynamo electric machine 1, is illustrated as connected by gears 2, 3, 4, to the shaft of the engine 6. This engine is for convenience illustrated as of the four-cylinder type having its cylinders 7, 8, 9, 10, arranged to receive a supply of explosive mixture through the manifold 11^a, and the carbureter 12^a, from a main supply tank 13^a, with intermediate connection 14^a.

60 The chassis frame is indicated at 15^a, and bears the various parts of the mechanism making up an ordinary chassis frame, the several parts of which need no detail description.

65 In the diagrammatic view illustrated in Fig. II, the engine cylinders 7, 8, 9, 10, are illustrated as provided with spark plugs 11 to 14, inclusive, which plugs, of course, have one of their terminals grounded in the engine and frame while the other is connected with the respective circuit wires 15 to 18, inclusive. These line-wires terminate in the relatively stationary contacts of the distributor, D, the movable contact 19, thereof 70 being connected with a circuit wire 20, which, through the secondary coil b', the primary coil b, of the spark coil B, is connected with the make and break device E, through its stationary contact e. The movable contact 21, actuated by a cam or suitable device 22, is connected through a line wire 23, with the switch contact 24. The opposite side of the circuit 26, which runs from the primary coil b, is connected with a 75 switch contact 27.

80 There are also two switch contacts 28, 29, which respectively connect with the circuit line wires 30, 31, that connect with the dynamo electric machine A.

85 This dynamo electric machine A, is, of course, provided with an armature, a, and with a series field winding G, and a shunt field winding F, which, through the circuit 30, 31, connect the dynamo electric machine 90 with a storage battery K, through the switch L, which, as indicated herein, is formed as a unit with the switch member l, that controls the lines 23, 26, of the ignition circuit that is

also connected with the storage battery K, and the main line wires of the dynamo electric machine when the switch L, l, is closed.

5 A lamp circuit 32, 33, is indicated as controlled by a switch M, which switch is connected with the line circuit 30^a, 31^a.

Of course, it is understood that the various controlling switches of the main line circuit 10 may be varied to suit any particular condition. It is preferred, however, that the switches L, l, are so arranged and interlocked that the main line circuit 30, 31, of the generator will be closed in relation to the 15 storage battery K, and main line 30^a, 31^a, only when the ignition circuit 23, 26, is closed. Otherwise, it is apparent that with the engine at rest, the storage battery K, might discharge through the dynamo electric 20 machine.

As illustrating the dynamo electric machine more in detail, reference is made to Figs. 3, 4 and 5, wherein the armature shaft 50, is illustrated as suitably mounted upon 25 anti-friction bearings 51, and attached to a gear 52, which gear is in mesh with a gear 53, mounted upon anti-friction bearings 54, and providing a means for rotating a make and break cam 55.

30 The armature 56 is provided with suitable commutator and brush connections arranged in the head-piece 57. These parts are not shown in detail nor are the fields arranged within the casing 58, specifically shown in 35 detail.

To the front of the main casing of the dynamo electric machine is secured a casing 59, which provides a suitable bearing for the support of the gear 52, and an axially movable sleeve 60. This sleeve, as illustrated 40 herein, is, through a spline 61, connected with a sectional shaft 62, which, in turn, is connected through the gears 2, 3, 4, with the main shaft of the engine.

45 The gear 52 has an extended sleeve 63, provided with helical slots or cam grooves 64, within which are arranged pins 65, that are secured to the axially movable sleeve 60. The sleeve 60 is also provided with a grooved 50 actuator 66, which, through any suitable lever 67, may be utilized to actuate a switch device such as illustrated in diagram at L, l, or for any purpose for controlling the various circuits.

55 In Figs. III and IV, I have illustrated the particular form of timing mechanism employed.

The gear 53 heretofore referred to and the timing cam 55, are mounted to rotate upon 60 the anti-friction bearings 54, which are supported upon a spindle 68, which spindle is secured in the face plate 69 of the machine in any desired manner.

An insulating plate 70, provided with 65 suitable conductors 71, to 74, inclusive, pro-

vides a means for bringing the inner terminals of said conductors successively into position to take current from the plate 75 on the rotating member 53. The opposite side of the circuit is connected through a 70 conductor 76 to a ring plate 76' and thence through the conductor 77 to the plate 75.

Secured in an insulating plate 78 is a stud 79 upon which is mounted a trip finger 80, held in normal position by a spring 81, and having a lip 82 and a lever arm 83. The latter comes in contact and is moved by the bosses 84 of the timing cam 55, so that the vibrating spring 85 will be drawn away from the contact point 86 at given periods to 80 break the circuit. The vibrator spring 85 is mounted in a block 87, in any suitable manner.

With this arrangement of parts, it is apparent that the timing device will always 85 operate synchronously with the generating apparatus and both devices are conveniently coalesced to form a unit which, with the ordinary controlling devices, may be mounted upon the engine in lieu of an ordinary 90 magneto.

In diagram in Fig. II there is illustrated a switch O, which may be utilized for making and breaking the ignition circuit. This, of course, is such a switch as is ordinarily 95 employed on automobiles and must be closed in order to effectively operate the other elements. On the other hand, to stop the engine, this ignition switch may be opened and thereupon the engine, through its reduced 100 speed, will permit battery K to drive the dynamo electric machine A as a motor and cause the automatic switch lever 67, to be moved through the sleeve 60 to properly cut out the ignition and generator circuits at 105 switches L, l, as hereinbefore described.

Obviously, the elements might be arranged in various forms of juxtaposition or the details of the mechanism might be varied without departing from the spirit or intent of 110 the invention, which, in the main, contemplates a generating apparatus combined with timing, ignition and lighting devices.

What I claim is:

1. In a device of the character described, 115 the combination with an electric machine including a rotor shaft, of a distributor device and a timing mechanism mounted on the same axis independently of said shaft and on one side of the electric machine, and driving means between the distributor and the electric machine and on the same side of the electric machine as the distributor and timing mechanism.

2. In a device of the character described, 125 the combination with an electric machine including a rotor shaft, of a casing for said machine including an end covering, a timing mechanism and distributor device mounted on said end covering independently of the 130

rotor shaft, and a driving connection between the rotor shaft and the distributor device and timing mechanism.

3. In a device of the character described, 5 the combination with an electric machine including a rotor shaft, of a casing for said electric machine including an end covering, a timing mechanism and distributor device mounted on the same axis on said end covering independently of the rotor shaft, and driving connections between the rotor shaft 10 and distributing device and timing mechanism.

4. In an ignition apparatus, the combination 15 with a rotatable cam, of a housing therefor, a pair of interrupter contacts mounted within said housing, a pivot pin secured therein, an interrupter actuating member having a cam contacting portion pivotally mounted on said pin and adapted to transfer motion from said cam member to one of 20 said interrupter contacts, and a resilient member mounted upon said pivot pin for normally holding the cam contacting portion 25 of said interrupter actuating member in operative position with respect to said cam.

5. In an ignition apparatus, the combination 30 with a rotatable cam, of a housing therefor, a pair of interrupter contacts mounted within said housing, a pivot pin secured therein, an interrupter actuating member having a cam contacting portion pivotally mounted on said pin and adapted to transfer motion from said cam member 35 to one of said interrupter contacts, and resilient means encircling said pivot pin for returning said interrupter actuating member to normal position after the same has been moved out of normal position by the 40 cam.

6. In an ignition apparatus, the combination 45 with a rotatable cam, of a housing therefor, an interrupter actuating member pivotally mounted within said housing and having a cam contacting portion adapted to transfer motion from said cam member to one of said interrupter contacts, and resilient means encircling the pivotal axis of 50 said contact actuating member for normally holding the cam contacting portion of said interrupter actuating member in operative position with respect to said cam.

7. In an ignition apparatus, the combination 55 with a rotatable cam, of a housing therefor, a fixed contact mounted within said housing and adjustable from the exterior thereof, a movable contact co-operating with said fixed contact and carried by a resilient controlled member, and actuating 60 mechanism for transferring motion from said cam pivotally mounted within said housing and including a cam contacting member, and resilient means for normally holding said cam contacting member in operative position 65 with respect to said cam.

8. In an ignition apparatus, the combination with a rotatable cam, of a housing therefor, a pair of interrupter contacts mounted within said housing, a pivot pin secured therein, an interrupter actuating member 70 having a cam contacting portion pivotally mounted on said pin and adapted to transfer motion from said cam member to one of said interrupter contacts, a resilient member mounted upon said pivot pin for normally holding the cam contacting portion of 75 said interrupter actuating member in operative position with respect to said cam, a high tension current distributor member carried by said cam, and means for mounting 80 said current distributing member on said cam in fixed angular relation thereto.

9. In an ignition apparatus, the combination 85 with a rotatable cam, of a housing therefor, a pair of interrupter contacts mounted within said housing, a pivot pin secured therein, an interrupter actuating member having a cam contacting portion pivotally mounted on said pin and adapted to transfer motion from said cam member to 90 one of said interrupter contacts, a resilient member mounted upon said pivot pin for normally holding the cam contacting portion of said interrupter actuating member 95 in operative position with respect to said cam, a high tension current distributor member carried by said cam, and means comprising a non-concentric opening in said cam and a member adapted to project therein from said current distributing member for 100 mounting said current distributing member on said cam on fixed angular relation thereto.

10. In an ignition apparatus, the combination 105 with a rotatable cam, of a housing therefor, a pair of interrupter contacts mounted within said housing, an interrupter actuating member pivotally mounted within said housing and having a cam contacting portion adapted to transfer motion from said cam member to one of said interrupter contacts, resilient means encircling the pivotal axis of 110 said contact actuating member for normally urging the cam contacting portion of said contact actuating member toward the cam, a high tension current distributing member carried by said cam, and means for mounting the current distributing member on said cam in fixed angular relation thereto.

11. An ignition apparatus for internal combustion engines comprising an engine driven cam, a shaft upon which said cam is concentrically mounted for relative rotation with respect thereto, a bearing member 115 mounted within a concentric recess formed in said cam said bearing member forming a bearing between said cam and said shaft, an adjustable contact, a movable contact co-operating with said adjustable contact, and 120 125

a member for transferring motion from said cam to said movable contact.

12. An ignition apparatus for internal combustion engines comprising an engine driven cam, a shaft upon which said cam is concentrically mounted for relative rotation with respect thereto, a bearing member mounted within a concentric recess formed in said cam said bearing member forming a

bearing between said cam and said shaft, an adjustable contact, a movable contact co-operating with said adjustable contact, a member for transferring motion from said cam to said movable contact, and an inclosing cap for said cam and contacts resiliently mounted upon said shaft. 15

In testimony whereof, I affix my signature.
JOHN ALLEN HEANY.
